BED-TYPE CHAIR

Lillie M. Leavitt, Lakeport, N. H.

Application May 28, 1945, Serial No. 596,196

4 Claims. (Cl. 5—70)

1

The present invention relates to a chair which is expressly constructed for use by sick and bed-ridden persons, the same being especially and suitably designed to occupy a satisfactory position atop the mattress, whereby to provide a convenient chair and support for the occupant of the bed.

Although the chair was expressly constructed, at the time of inception, for use in connection with hospital beds, it is obviously, and equally well adapted for use in the home, and places of convalescence and recreation.

Briefly, the preferred chair is characterized by a suitable frame which is adapted to fit firmly and horizontally on the mattress, this part of the structure being provided with confining sides and arm-rests and being expressly designed to accommodate a tiltably adjustable back-rest.

More explicitly, the chair proper comprises a pair of spaced, parallel, horizontal rails to rest upon the mattress, uprights connected to and rising from said rails, and auxiliary rails above the main base rails, said auxiliary rails constituting side guards and arm rests, and being constructed at their rear ends to appropriately confine and adjustably support a back-rest, the latter hingedly connected to the rear end portions of the base rail.

Other objects, features and advantages of the invention will become more readily apparent from the following description and the accompanying illustrative drawing.

In the drawing, wherein like numerals are employed to designate like parts throughout the views:

Figure 1 is a front elevation of a bed chair constructed in accordance with the principles of the present invention showing the same set up and ready for use.

Figure 2 is a side view of same illustrating it positioned on a mattress and also showing the adjustable positions of the back-rest.

Figure 3 is a bottom plan view.

Figure 4 is an enlarged detail section on the line 4—4 of Figure 2 to show the latch construction, certain of the parts being omitted for clearness of illustration.

Figure 5 is an enlarged view showing how the table board is slidably mounted and held in place.

The structure, considered in general language, is characterized by the chair proper denoted at A and the complementary back-rest, the latter denoted at B. The back-rest is the simplest of the two parts in form, and comprises a frame embodying vertical members 6, top and bottom

2

members 7 and 8 and suitably attached and spaced slats 9. The side members are mortised, as shown in Figure 4, to accommodate, in each instance, the projecting portion 10 of a latch plate 11. The latter is screwed or otherwise fastened in place and the part 10 is socketed to accommodate a coil spring 12. The spring serves to project the keeper end 13 of the head-equipped latch pin or plunger 14.

10 The chair A comprises a pair of spaced parallel bottom or base rails 15, these being adapted to sit flat on the mattress 16, as shown in Figure 2. Inwardly of the rear end is a substantially U-shaped strap 17 having its outer end portions secured to the top surfaces of the base rails 15, the free ends being upturned to provide accommodation ears or lugs 18 to which the hinge pintles 19, on the back-rest B, are connected. This U-strap 17 is the main means of connecting the 20 rails together.

I now call attention to a plurality of uprights 20, 21 and 22, as seen in Figure 2, these having their inner, laterally-directed, lower ends 23 riveted or otherwise secured to longitudinally spaced portions of the respective base rails 15.

25 Next, I call attention to the upper or auxiliary chair rails 24. I provide a pair of these disposed in parallelism and of angular form. The horizontal, inturned flanges are denoted at 25 and 30 are reinforcing elements as well as ledges. The upper ends of the uprights 20, 21 and 22 are riveted to the vertical flanges of said rails 24. As seen in Figure 5, a slide board or suitable plate 26 is provided, it being of general rectangular form, this part serving as a general utility table. Its outer, transverse ends slide on the ledge flanges 25 and said flanges have channels 27 formed in their under surfaces. The channels constitute keyways and serve to accommodate the 35 keys or detents 28 carried by the keying cleats 29 bolted or otherwise secured to the under surface of the table board 26. It will be noted that these flanges 25 stop short of the point occupied by the back-rest B when said back-rest is in perpendicular position, as shown in Figure 2. Thus, the rear or terminal end portions of the rails constitute 40 adapters and are denoted by the numerals 30. The curve slightly down and have their free ends inturned and riveted to a cross-strap 31. This 45 serves as a rest for the rearmost and inclined position of the back-rest, as shown at the right in Figure 2. It is also to be noted that these downturned end portions 30 are provided with longitudinally spaced apertures which constitute 50 keepers 32 for selective reception of the ends 13

of the spring-pressed latch bolts 14. Consequently, the hinged back-rest can be adjustably positioned and held, at a desired inclination, between the apertured portions 30 of said chair or auxiliary rails 24.

It is to be observed that there are no obstructions between the outer end portions of the main base rail 15. Consequently, the patient actually sits directly on the mattress between said rails. The uprights and auxiliary side rails constitute confining sides as well as arm rests to aid in supporting the patient. The table 26 comes in handy for reading, eating, and other useful purposes. The back-rest is lightweight, yet sturdy, and easy to adjust, making it possible for the patient to recline to a position of requisite comfort.

Finally, my improved chair, with back-rest and side arms, can be used to advantage as a convenient support for patients that need a sitting position in bed, such as with heart disease. The side arms serve as a protection against falling sideways when patients are unconscious or semi-conscious.

It is thought that persons skilled in the art to which the invention relates will be able to obtain a clear understanding of the invention after considering the description in connection with the drawing. Therefore, a more lengthy description is regarded as unnecessary.

Minor changes in the shape, size and arrangement of details coming within the field of invention claimed may be resorted to in actual practice, if desired.

I claim:

1. A bed chair of the class described comprising an open-bottom chair including a pair of spaced, parallel, relatively wide base rails adapted to sit firmly and horizontally on a mattress in order to use the mattress as a seat, said chair including confining sides and arm rests, and an adjustably mounted back-rest, auxiliary side rails, spaced above and parallel to said base rails and curving downwardly at their rear and having a transverse back stop secured to their extremities, a plurality of apertures in said downwardly curving portion, and spring extended plungers, manually retracted, removably socketed in said

back rest for selective engagement in said apertures to adjustably secure said back rest to said side rails.

2. A bed chair of the class described comprising a pair of spaced, parallel, relatively wide base rails adapted to sit directly and firmly on a bed mattress, uprights connected to and rising from said base rails, auxiliary side rails connected to the upper ends of said uprights and disposed horizontally above and parallel to the base rails, said auxiliary rails having inturned flanges forming ledges, said ledges serving as supporting guides, a table-board slideable on said ledge-guides, side grooves extending longitudinally on the under surface of said ledge guides, retaining plates secured to said table board and embracing said ledge guides, and guide portions on said retaining plates slidably disposed in said guide grooves.

3. A bed chair of the class described comprising a pair of spaced, parallel, relatively wide base rails adapted to sit directly and firmly on a bed mattress, uprights connected to and rising from said base rails, auxiliary side rails connected to the upper ends of said uprights and disposed horizontally above and parallel to the base rails, said auxiliary rails having inturned flanges forming ledges, said ledges serving as supporting guides, a table-board slideable on said ledge-guides, the undersides of said ledge guides having channels forming key-ways, and cleats on the underside of said table-board, said cleats having detents forming keys and said keys being slideable in said key-ways.

4. A bed chair comprising a pair of spaced, parallel base rails, a U-strap having its end portions connected to the rear end portions of said base rails and securing said base rails together, the upturned outer ends of said U-strap constituting ears, a back-rest having hinge pins mounted in said ears, auxiliary rails, uprights supporting the auxiliary rails from and above said base rails, the rear end portions of the auxiliary rails being connected together by a stop strip and being downturned and apertured, as shown and described.

LILLIE M. LEAVITT.
